UNITED STATES PATENT OFFICE.

KONRAD JAGSCHITZ, OF MAINZ, GERMANY, ASSIGNOR TO MASCHINENFABRIK AUGSBURG-NUERNBERG A. G., OF NUREMBERG, BAVARIA, GERMANY, A CORPORATION OF GERMANY.

METHOD AND ARRANGEMENT FOR THE ERECTION OF DRY GASOMETERS.

Application filed December 26, 1923. Serial No. 682,842.

To all whom it may concern:

Be it known that I, KONRAD JAGSCHITZ, a citizen of Germany, of No. 27 Weintorstrasse, residing at Mainz, Germany, have 5 invented certain new and useful Improvements in a Method and Arrangement for the Erection of Dry Gasometers, of which the following is a specification.

The erection of dry gasometers having 10 slideable discs to close the variable gas space takes place, as a rule, by suspending the previously constructed closing disc as a working stage or platform upon a mast or upon the wall posts of the gasometer so 15 as to be slideable thereon and adjustable at any desired height, in order to enable an exact fitting of the plates forming the outer shell of the gasometer.

This known method admittedly gives the 20 desired amount of accuracy in the fitting of the plates, but it requires a special time consuming adjustment or alinement of the wall posts, the position of which has to be continuously measured and re-examined.

25 The object of this invention, therefore, is to eliminate this measuring work and to thus save time and labour, and it mainly consists in a method and an arrangement to positively and forcibly carry out the required alinement by means of the closing disc itself. In order to thereby avoid undue 30 stresses in the wall posts and consequent distortions, such as are likely to occur when pulling the disc up the said wall posts; 35 the disc is preferably raised by means of compressed air pressure from below in a manner which in itself is known.

In this way it is possible to obtain a permanent correct position of the disc itself 40 as well as of the wall posts which are positively alined by the disc during its upward travel, so that the fitting of the wall plates may be effected without having to continuously measure and re-examine the 45 measurements, whereby time and labour may be saved.

The means for carrying out the new method of wall post adjustment may be chosen to suit each particular case. In a 50 preferred form of the invention, however, special auxiliary frames are used, which closely embrace the posts and which are

temporarily fixed to such parts of the closing disc, or to the strengthening ring thereof, which correspond to the positions of the 55 guide rollers of the disc, or of the wall posts respectively. The said auxiliary frames are provided with auxiliary guide rollers by means of which the individual posts are pressed against the guide rollers 60 of the disc and thereby alined in position. The auxiliary rollers are contoured in the manner of stepped pulleys and they are arranged with their stepped surfaces bearing against the narrow sides and the reverse side of a flat rail which, for the purpose, is fixed to each of the wall posts. 65

The drawing illustrates an arrangement according to the invention by way of example.

70 Fig. 1 shows the auxiliary frame with part of the strengthening girder work of the closing plate and one of the wall posts in side elevation.

Fig. 2 is a plan view of Fig. 1.

Fig. 3 is a vertical section of a gasometer equipped with the invention and Fig. 4 is a fragmentary plan view thereof.

75 In the drawings 1 denotes the guide roller of the closing disc, hereinafter called the main guide roller, which is carried by a jib-like frame 2 of the strengthening girder work 3 of the closing disc *a*. To this frame 2 is temporarily fitted an auxiliary frame 5 arranged to enclose the wall post 4 of the gasometer and carrying a pair of auxiliary guide rollers 6 which are contoured in the manner of stepped pulleys and of which the stepped surfaces are adapted to press 80 against a flat rail 7 fixed to the wall post 4 in such a manner, that this rail, and therewith the said wall post, are pressed against the main guide roller 1 and thus effectively secured against lateral displacement. An 85 undesired displacement of the jib-frame 5 may be prevented by the provision of ties 8.

90 It will be seen from the drawing that on the closing disc being raised from below, for example by means of compressed air, the said rollers 1 and 6 press against the rail 7 at all of its four sides thus causing 95 the wall posts 4 to be alined by the movement of the disc, which latter thereby serves as an alinement template. The wall plates 100

9 may then be fixed in position without a re-examination of the measurements being necessary.

What I claim is:—

1. A method for the erection of dry gasometers having closing discs, which serve in each case as a working stage during erection, said method consisting in raising the disc along the wall posts of the gasometer and operating thereby a means whereby the said wall posts by the movement of the disc itself are simultaneously aligned.

10 2. A method for the erection of dry gasometers having closing discs, which serve in each case as a working stage during erection, said method consisting in raising the disc from below as by means of compressed air along the wall posts of the gasometer and operating thereby a means whereby the said wall posts by the movement of the disc itself are simultaneously aligned.

15 3. An arrangement for the alinement, during the erection of dry gasometers, of the wall posts thereof comprising in combination with the closing disc of the gasometer and the main guide rollers thereof, of auxiliary frames adapted to enclose each of the wall posts, and means on the auxiliary 20 frames to press the said wall posts into close contact with the main guide roller during the upward travel of the closing disc.

30 4. An arrangement for the alinement, during the erection of dry gasometers, of the wall posts thereof, comprising in combination with the closing disc and the main guide rollers thereof, of temporarily fixed

auxiliary frames enclosing the said wall posts, auxiliary guide rollers in the said frames to press the wall posts into close contact with the main guide rollers during the upward travel of the closing disc.

40 5. An arrangement for the alinement, during the erection of dry gasometers, of the wall posts thereof comprising in combination with the closing disc and the main guide rollers thereof, of auxiliary frames temporarily fixed to the strengthening ring of the closing disc and each enclosing wall post, auxiliary guide rollers in the said frames to press the wall posts into close contact with the main guide rollers during the upward travel of the closing disc.

45 6. An arrangement for the alinement, during the erection of dry gasometers, of the wall posts thereof comprising in combination with the closing disc and the main guide rollers thereof, of a flat rail in fixed connection with each of the wall posts, auxiliary frames temporarily fixed to the closing disc, each frame enclosing a wall post and the flat rail connected therewith, auxiliary guide rollers in the said frames of stepped pulley formation pressing against the opposite edges and the outer surfaces of the flat rails so as to keep the said rails in close contact with the main rollers during the upward travel of the closing disc.

50 65 In testimony whereof I affix my signature 70 in presence of two witnesses.

KONRAD JAGSCHITZ.
